(57) **CLAIM**

The ornamental design for a combined golf club cleaning device with extendable and retractable clip, as shown and described.

DESCRIPTION

FIG. 1 is a rear perspective view of a combined golf club cleaning device with extendable and retractable clip showing our new design;

FIG. 2 is a front perspective view of the combined golf club cleaning device with extendable and retractable clip;

FIG. 3 is a top plan view of the combined golf club cleaning device with extendable and retractable clip;

FIG. 4 is a side elevational view of one side of the combined golf club cleaning device with extendable and retractable clip;

FIG. 5 is a front elevational view of the combined golf club cleaning device with extendable and retractable clip;

FIG. 6 is a bottom plan view of the combined golf club cleaning device with extendable and retractable clip;

FIG. 7 is a rear perspective view of a combined golf club cleaning device with extendable and retractable clip as attached to an extendable and retractable clip;

FIG. 8 is a front perspective view of the combined golf club cleaning device with extendable and retractable clip as attached to an extendable and retractable clip;

FIG. 9 is a top plan view of the combined golf club cleaning device with extendable and retractable clip as attached to an extendable and retractable clip;

FIG. 10 is a front elevational view of the combined golf club cleaning device with extendable and retractable clip as attached to an extendable and retractable clip; and,

FIG. 11 is a side elevational view of the combined golf club cleaning device with extendable and retractable clip as attached to an extendable and retractable clip.
